PNEUMATIC HYDRAULIC VISE

Frederick W. Kent, Chicago, Ill.

Application July 27, 1942, Serial No. 452,391

8 Claims. (Cl. 90—60)

1

This invention relates to improvements in a vise adapted to be mounted upon the work table of a milling machine or other machines wherein a means for holding an object to be worked upon may be required or desirable.

The object of the invention is to provide a structure of the type specified which is operated hydraulically to clamp the work in place, and which is equipped with interchangeable jaws to receive articles of different dimensions and which is also provided with means for varying the spacing apart of such jaws and with means for effecting quick release of the work when desired or necessary.

Another object of my invention is the provision of a vise in which both pneumatic and hydraulic pressure affects the locking of the work-piece in the vise. Vises utilizing pneumatic or hydraulic pressure and particularly pneumatic pressure, as a locking means, have, because of the need for variable pressure, on different size work-pieces resorted to a large and cumbersome cylinder or cylinders to provide the maximum pressures required. The "step-up" of locking pressure of my vise eliminates this objectionable feature and a much smaller, more sturdy, compact vise, with a large work-piece capacity results.

Other objects and advantages of the invention will be readily understood from the following description and, in part at least, are particularly pointed out therein.

A suitable embodiment of the invention is illustrated in detail in the accompanying drawings which are, in part, more or less diagrammatic in that they omit certain conventional details of construction common to fluid pressure actuated machinery.

In said drawings,

Fig. 1 is a top plan view of the vise constructed in accordance with the invention.

Fig. 2 is a side elevation thereof with my parts shown in vertical longitudinal section.

The said vise comprises a base plate 10 which is equipped peripherally with recesses 11, 12, 13 and 14, respectively, to receive the shanks of bolts by means of which said base plate is rigidly mounted upon the frame of the machine. It is desired to call attention to the fact that the recesses 11, 12, 13 and 14 complement the ways of the standard milling machine carriage so that my vise may be secured thereto without special fixtures.

The said plate 10 is equipped with suitable parallel guide formations 15 and 15' with which

2

the base portions of the respective vise jaw members 16 and 17 are slidably engaged. The structure includes a member 18 which is rigid with the base plate and is equipped with a vertically disposed pocket 27 to receive a suitable liquid, such as oil, and is equipped at its upper end with suitable closure plugs 27a and 27b, respectively, the latter being equipped with a stop projection 27c opposed to the end of a piston 26 which is reciprocably movable in a passage or cylinder communicating with the pocket 27 and is rigid with the vice jaw member 16 which it actuates.

In the lower end of the member 18 there is provided a cylindrical passage 27d which receives the piston 29 secured to the piston rod 30 of the piston 32 of cylinder 33, said piston 30 extending through the bearing 31 of the said cylinder. The passage to receive the rod 29 may be termed a cylinder which communicates at point 28 with the pocket 27.

The vise jaw members 16 and 17 are equipped with removable work engaging jaws 20 and 21 which are equipped with recesses 20' and 21' in their opposed faces and are adapted to be replaced by other jaw elements having variously shaped recesses in which the work is to be engaged.

Rigid with the base plate 10 is a pair of flanges 10d equipped with inwardly projecting ears 10e through which the shanks of screws 24 and 25 extend freely for movement with respect to said ears, said screws being engaged in threaded openings in the vise jaw member 16. Compression springs 22 and 23 of suitable length and strength are interposed between the ears 10e and the heads of the screws 24 and 25, or washer engaged with said heads as shown.

The cylinder 33 is equipped with ports 33a and 33b, respectively, the former being connected with the valve casing 34 equipped with a two-way valve adapted to be actuated by the lever 35. Said valve casing is equipped with an exhaust port 34a and is connected by means of pipe 36 with a source of supply of fluid under pressure, such as air, which is admitted to the cylinder 33 when the valve is in the position shown. Said valve is adapted to be rotated through an arc of 90° to connect the port 33a with the exhaust port 34a to relieve pressure in the cylinder at one end 50 of the piston 32. Obviously the port 33b may be controlled by a similar two-way valve for actuating the piston in the direction opposite to that in which it is moved when the valve of casing 34 is in the position shown.

It will be noted of course that the diameter

of the piston 32 is many times that of the piston rod 29 so that the pressure exerted by the latter upon the liquid contained in the pocket 27 will be subjected to many times the pressure exerted upon the piston 32 by compressed air or other fluid entering the port 33a. This particular feature of my vise is of substantial importance since it is one of the factors which permits a substantial "step-up" of the pressure exerted by the jaw 16 as compared with the fluid pressure exerted against the piston 32. Another factor that controls the "step-up" of pressure is the comparative length of stroke or travel of the pistons 29 and 26. Thus the "step-up" of jaw pressure can be regulated without resorting to mechanical leverage or large cumbersome cylinders. As a matter of practical engineering a force of 50 to 60 times the air or fluid line pressure is exerted at the jaws of my vise.

Rigid with the jaw member 17 is a member 40 shown in section in Fig. 2, which is provided with a substantially semi-cylindrical bottom bushing threaded to engage the screw shaft 37 which is also threaded through the member 10c rigidly with the base plate 10 and is adapted to be actuated manually by the crank arm 39. The bushing 38 is rigidly mounted in the member 10c as is customary.

Threaded through the top wall of the member 40 is a set screw 41 which is rotatably connected at its lower end with a substantially semi-cylindrical nut 41a which is adapted to be clamped tightly upon the screw shaft 37 to hold the latter against rotation and thus hold the vise jaw 17 rigidly in any position to which it may have been adjusted by rotation of the crank 39 after the nut portion 41a relieves pressure on the screw shaft 37.

The operation of the structure above described is as follows:

It will be noted that the springs 22 and 23 operate to maintain the jaw member 20 normally in engagement with the flanges 10d and serve also to maintain the piston 26 at the rearward limit of its movement as shown in Fig. 2. If desired, however, the stop projection 21c may be disposed to constitute the means for limiting the reverse movement or work disengaging movement of the jaw 16 in place of utilizing the forward edges of the members 10b as stops as aforesaid. If the springs 22 and 23 are strong enough to effect movement of the piston 32 to the right when the valve of casing 34 connects cylinder 33 with the exhaust port 34a, then the port 33b will not require connection with a valve as above described but will merely constitute a vent.

Assuming the piston 32 to be disposed at the right-hand limit of its movement, then by setting the valve connected with the port 33b (if such valve is provided) to the position wherein air from the left-hand chamber of the cylinder may be exhausted to atmosphere, and then positioning the valve of the casing 34 in the position shown in Fig. 2, the piston would be forced to the limit of its forward movement as determined by the engagement of the work jaw 16 with the work, it being obvious that this might be substantially any point between the ends of the cylindrical passage receiving the piston 29. The piston 29 as it is advanced in the cylindrical passage has displaced the oil, or other liquid, from said passage into the chamber 27 where the oil so displaced has in turn actuated the piston 26 and the jaw 16 into engagement with the work-piece.

When this position is attained, the valve of cas-

ing 34 may be closed by rotating it through an arc of about 45° or it may be retained in the position shown in Fig. 2 to maintain the cylinder connected with the source of fluid under pressure. With the valve in its closed position, it may be disconnected from the air pressure source, and the work-piece will still be securely gripped. Obviously, the disengagement of the valve from the fluid or air pressure source will facilitate the working of the work-piece and, in addition removes the possibility of injuring either the work-piece or the operator utilizing my vise should a fluid pressure failure occur.

When it is desired to release the work and remove it, the valve of casing 34 will be rotated anti-clockwise through an arc of 90° to connect the port 33a with the exhaust port 34a and the valve (if provided) controlling the port 33b would then be turned to admit compressed air through said port and thus force the piston 32 back to its normal position at the right-hand end of the cylinder 33. The piston 29 is also withdrawn from the cylindrical passage and the oil of chamber 27 seeks the lower level of the cylindrical passage vacated by the piston 29 so that the pressure on piston 26 is released and the springs 22 and 23 retract the piston 26 and jaw 16 from engagement with the work-piece to the position shown in Fig. 2.

If by chance it should be necessary to move the jaw 21 to the right from the position shown in Fig. 2, the set screw 41 will be rotated to relieve pressure on the nut portion 41a and the crank 39 then rotated to cause the jaw 21 to be moved to the right. After releasing the work and replacing it with a new piece or pieces, the crank 39 will be again operated until the jaw 21 is in its desired position, the screw-shaft then clamped against rotation and thereafter the foregoing operations repeated so far as manipulation of the valve or valves is concerned. It is to be understood that the specific means for actuating the jaw 21 and of securing it in a pre-determined position is only one mechanical expedient, that other equivalent means may be substituted by persons skilled in the art, and that such changes are within my contemplation.

The drawings are diagrammatic in so far as they omit illustration of such conventional structural details as the inclusion of proper packing rings about the piston rod 30 and the piston 29 or omit stuffing boxes commonly used.

The words "fluid pressure" as used herein in conjunction with or referring to the valve 34 and the cylinder 33 are to be construed as inclusive of such gases as might be used for such a pneumatic application but shall not be construed as meaning or including liquids. The specifying of oil as the hydraulic medium used in the chamber 27 is not one of limitation, since other liquids might serve equally as well.

I claim:

1. In a vise, the combination with a bed provided with a guideway and a movable jaw mounted for reciprocation longitudinally of the guideway, of a hydraulic cylinder behind said jaw, a second hydraulic cylinder below the bed and disposed longitudinally of the guideway, a piston in the first cylinder and connected with the jaw, a conduit affording communication between said cylinders, a hydraulic liquid in the conduit and the respective cylinders, a single stroke plunger in the second cylinder, the liquid in the cylinders and conduits being confined between said plunger and piston, and means for the reciprocation of

said plunger beneath the bed to effect longitudinal movement of the jaw along the guideway.

2. The device of claim 1 in which the means for effecting plunger movement comprises a pneumatic cylinder and piston below the bed, the pneumatic piston being directly coupled with said plunger and the pneumatic cylinder being provided with a pneumatic pressure line and control valve means for admitting and exhausting pressure.

3. The device of claim 1 in which the means for effecting plunger movement comprises a pneumatic cylinder and piston below the bed, the pneumatic piston being directly coupled with said plunger and the pneumatic cylinder being provided with a pneumatic pressure line and a control valve for admitting and exhausting pressure, the hydraulic cylinder below the bed being of materially reduced cross section as compared with the hydraulic cylinder behind the jaw and the pneumatic cylinder being of large cross section in proportion to the pressure supply line, whereby a moderate pressure in the supply line will exert greatly increased pressure at the jaw.

4. A vise comprising a hollow base, a bed extending longitudinally of said base and provided with a longitudinal guideway, a first jaw adjustable longitudinally of the bed and provided with means for fixing it in adjusted position, a second jaw movable along the guideway toward and from the first jaw, a hydraulic cylinder behind the second jaw, a piston in the cylinder connected with the second jaw, means biasing the second jaw for movement along the guideway away from the first jaw, a liquid conduit leading to the hydraulic cylinder, a second hydraulic cylinder with which said conduit communicates, said second hydraulic cylinder being disposed longitudinally of the base below the bed, a plunger in the second hydraulic cylinder, said plunger and second cylinder being of materially smaller area in cross section than the hydraulic cylinder first mentioned and its piston, a pneumatic cylinder extending longitudinally of the base below the bed and of cross sectional area greatly exceeding that of the second hydraulic cylinder, a piston in the pneumatic cylinder and projecting toward said plunger, means coupling the pneumatic piston to said plunger, a pneumatic supply line, control valve means for admitting pneumatic fluid from said line to the pneumatic cylinder and for releasing pneumatic fluid from the pneumatic cylinder, and a liquid confined in the hydraulic cylinders and communicating conduit between the hydraulic piston and said plunger, said liquid serving to transmit motion between the plunger and the second vise jaw according as the pneumatic piston is subjected to pressure or relief of pressure in the pneumatic cylinder.

5. A vise comprising a bed affording a longitudinal guideway, a first jaw provided with means fixing it to said bed, a second jaw movable along the guideway toward and from the first jaw, hydraulic cylinder and piston means above the bed and operatively connected for actuating the sec-

ond jaw, a liquid conduit leading to the hydraulic cylinder and piston means from a point below the bed, a second hydraulic cylinder and piston means disposed below the bed and communicating with said conduit, the second hydraulic cylinder and piston means being materially smaller in cross-sectional area than the hydraulic cylinder and piston means first mentioned, a pneumatic cylinder and piston means below the bed and operatively connected with the second hydraulic cylinder and piston means for effecting liquid displacement therein and otherwise mechanically independent of said second hydraulic cylinder and piston means, a hydraulic liquid confined in the first and second mentioned hydraulic cylinder and piston means and the conduit therebetween, and means for admitting pneumatic fluid to and exhausting pneumatic fluid from the pneumatic cylinder.

20 6. The vise set forth in claim 5 in which the first mentioned hydraulic cylinder and piston means comprises a spring biasing the piston from the cylinder in a direction to retract the second jaw respecting the first jaw of the vise.

25 7. In a vise, the combination with a bed providing a guideway, a first jaw having means fixing it upon said bed and a second jaw movable along the guideway to and from the first jaw, of a hydraulic cylinder behind the second jaw, a second hydraulic cylinder below the bed and disposed longitudinally of the guideway, a piston in the first cylinder connected with the second jaw, a conduit affording communication between the cylinders, a hydraulic liquid in the conduit and respective cylinders, a single stroke plunger in the second cylinder, the liquid in the cylinders and conduits being confined between the plunger and the piston, a pneumatic cylinder independent of the second hydraulic cylinder and disposed below the bed and longitudinally of the guideway, a piston in the pneumatic cylinder having a connecting rod projecting toward the second hydraulic cylinder, a coupling connecting the connecting rod of the pneumatic piston with said plunger for the operation thereof, and means including an air supply line and control valve for admitting fluid pressure to and exhausting fluid pressure from the pneumatic cylinder for acting on the piston thereof to actuate said plunger for the displacement of a hydraulic liquid from the second hydraulic cylinder and said conduit to the first hydraulic cylinder for the operation of said second jaw.

55 8. The device set forth in claim 7 in which the first mentioned hydraulic cylinder comprises a compression spring seated between the end of the cylinder and the piston therein and acting upon said piston in a direction to oppose the admission of hydraulic liquid to such cylinder and, 60 upon the release of pneumatic pressure in the pneumatic cylinder to displace hydraulic liquid from the first mentioned cylinder toward the second mentioned hydraulic cylinder and thereupon to retract said second jaw along said guideway.

FREDERICK W. KENT.
